UNITED STATES PATENT OFFICE.

JAMES FRANK DUNLEAVY, OF NEWTON, MASSACHUSETTS.

DESK.

1,093,981.

Specification of Letters Patent. Patented Apr. 21, 1914.

Application filed October 7, 1912. Serial No. 724,235.

To all whom it may concern:

Be it known that I, JAMES FRANK DUNLEAVY, a citizen of the United States, residing at Newton, in the county of Middlesex 5 and State of Massachusetts, have invented new and useful Improvements in Desks, of which the following is a specification.

My invention relates to roll-top desks and it has for its object to improve the construction of desks of this class.

My improved desk comprises a body made with one or more tiers of drawers; a master drawer preferably provided with a key-operated lock, a flexible roll top, and means 15 for locking the roll top and tier of drawers in their closed positions, said locking means being controlled and operated by the master drawer so that when the latter is opened the roll top and tier of drawers are unlocked and when the master drawer occupies its closed position it maintains or renders said locking means operative.

Other features of my invention are hereinafter pointed out.

25 In the accompanying drawings: Figure 1 is a vertical sectional view of a roll top desk embodying one form of my invention; Fig. 2 is a section on line 2—2 of Fig. 1.

Having reference to the drawings 1 represents the frame of my improved desk, 2 the flexible roll top mounted in guideways on frame 1, 3 the master drawer and 4, 4, 4, and 5, two tiers of drawers mounted within and at each side of frame 1 as usual. The 35 master drawer 3 occupies the position of the usual middle drawer and is slidably mounted in frame 1 between the two topmost drawers 4 and 5 in the usual fashion. The master drawer 3 is provided near its inner 40 end with two laterally projecting studs 6, 6 coöperating with the cam shaped or inclined ends of two levers 7 fastened rigidly to a rock shaft 8 journaled at its ends in frame 1. The levers 7 carry a bar 9 on 45 which are pivotally mounted the upper ends of two lock bars 10, 10 which are held against sidewise or lateral displacement by pins 11 engaging slots 12 provided in brackets 13 fastened to frame 1. Each lock bar 10 50 has connected with it the lower end of a spring 14 whose upper end is fastened to one of the brackets 13. The lock bars 10 are provided with laterally projecting hooks 15, one for each drawer 4 and 5, adapted when in engagement with the inner

ends of said drawers, as shown in Fig. 1, to lock said drawers in their closed positions.

The master drawer 3 is provided with a key operated lock 16 by means of which it is fastened in its closed position. When 60 the bolt of this lock is retracted and drawer 3 pulled out slightly, the studs 6, 6 are drawn away from levers 7, 7 thereby permitting the springs 14 to raise lock bars 10 far enough to unlock all of the drawers 65 4 and 5 so that it is unnecessary to open the roll top 2 in order to unlock drawers 4 and 5 as heretofore. As desks of this type have heretofore been constructed it was possible to split the top 2 between two of its "rolls" 70 with a knife and throw back the rear portion and thereby unlock all of the drawers of the desk, but it will be seen that such is not the case with the construction described.

On the rock shaft 8 are fastened two arms 75 17, 17 each of which supports a thimble 18 within which is telescopically mounted the lower end of a plunger 19 mounted to slide endwise in guides 20 on frame 1. The lower end of plunger 19 rests upon a spring 21 80 within thimble 18 while the upper end of said plunger coöperates with a socket 22 provided in the rear bar 23 of the top 2. When master drawer 3 is slid back into its closed position the studs 6 engage the inclined or beveled ends of levers 7 and swing the latter in opposition to springs 14 in a direction to lower bars 10 into drawer locking positions and at the same time the movement thus imparted to shaft 8 acts through 85 arms 17 and springs 21 to yieldingly force plungers 19 upwardly so that if top 2 then occupies its closed position the upper ends of plungers 19 are carried into sockets 22 thereby locking top 2 closed. If top 2 is not in 90 its closed position when plungers 19 are thus raised then the upper ends of said plungers will be yieldingly held against the inner side of top 2 so that when said top is closed they will be projected into the sockets 95 22. It will be clear, also, that when master drawer 3 is unlocked and opened to unlock drawers 4 and 5, the plungers 19 will be 100 simultaneously lowered to unlock top 2. The spring 21 permits of drawer 3 being 105 closed while top 2 is in either its open or closed position.

In order to maintain drawers 4 and 5 unlocked after the desk has been opened up and at the same time to provide for leaving 110

the drawer 3 in substantially closed position I provide a pair of levers 24 fixed to a rock shaft 25 journaled at its ends in frame 1, said levers being pivotally connected at one end with bar 9 and having their opposite ends arranged to support two vertical plungers 26 slidably mounted on frame 1. The upper ends of the plungers 6 are arranged in the path of the bar 23 of top 2 so that when 10 said top is thrown open said bar comes into a position immediately above the upper ends of the plungers 26 thereby locking the bars 10 in their uppermost positions with drawers 4 and 5 unlocked. Of course with the 15 locking mechanisms thus held in their inoperative positions by top 2 the front ends of levers 7 will be held depressed so that drawer 3 cannot be completely but can be substantially closed. That is, it can be slid 20 inward until the studs 6 engage the ends of levers 7.

What I claim is:

1. A desk of the character described comprising a tier of drawers; a master drawer; 25 a roll top; means operated by movement of the master drawer for locking the drawers of the tier in their closed positions, and means operated by movement of the master drawer for locking the roll top in its closed 30 position, said latter means being yieldingly mounted to permit operation of the tier locking means without regard to the position of the roll top with respect to its locking means.
2. A desk of the character described comprising a tier of drawers; a master drawer; a roll top; means operated by movement of the master drawer for locking the drawers of the tier in their closed positions; means 35 operated by movement of the master drawer for locking the roll top in its closed posi-

tion, said latter means being yieldingly mounted to permit operation of the tier locking means without regard to the position of the roll top with respect to its locking means, 45 and means through which the roll top when in its fully open position acts to hold both locking means inoperative.

3. A desk of the character described comprising a drawer, a master drawer, a lock bar slidably mounted in the desk in rear of said drawers, a spring for actuating the lock bar in one direction, a hook carried by said lock bar to engage the drawer, a lever pivotally mounted in the desk and connected to 50 the lock bar, means carried by the master drawer to operate the lever in one direction, a roll top for the desk, a locking member for said roll top, and a yieldable connection 55 intermediate said member and lever. 60

4. A desk of the character described comprising a drawer, a master drawer, a lock bar slidably mounted in the desk in rear of said drawers, a spring for actuating the lock bar in one direction, a hook carried by said 65 lock bar to engage the drawer, a lever pivotally mounted in the desk and connected to the lock bar, means carried by the master drawer to operate the lever in one direction, a roll top for the desk, a locking member 70 for said roll top, a yieldable connection intermediate said member and lever, and means operatively connected with the lock bar and adapted to be operated by the roll top in the movement of the latter in one 75 direction.

Signed by me at Boston, Mass., this fifteenth day of April, 1912.

JAMES FRANK DUNLEAVY.
